BOTTLE COASTER

Florence D. K. Haars, Beaufort, S. C.

Application February 19, 1952, Serial No. 18,588

Term of patent 14 years

(Cl. D44—10)

To all whom it may concern:

Be it known that I, Florence D. K. Haars, a citizen of the United States, residing in Beaufort, in the county of Beaufort and State of South Carolina, have invented a new, original, and ornamental Design for a Bottle Coaster, of which the following is a specification, reference being had to the accompanying drawing, forming a part thereof.

Fig. 1 is a top plan view of an unfolded bottle coaster showing my new design; and

Figs. 2 and 3 are, respectively, front and rear elevational views showing the coaster as it appears folded and tied around a bottle.

I claim:

The ornamental design for a bottle coaster, as shown and described.

FLORENCE D. K. HAARS.
